DESIGN FOR AN ELECTRIC CONNECTOR
PLUG OR SIMILAR ARTICLE

William H. Cook, Toledo, Ohio

Application June 13, 1946, Serial No. 130,669

Term of patent 14 years

(Cl. D26—1)

To all whom it may concern:

Be it known that I, William H. Cook, a citizen of the United States of America, residing at Toledo, Lucas County, Ohio, have invented a new, original, and ornamental Design for an Electric Connector Plug or Similar Article, of which the following is a specification, reference being had to the accompanying drawing, forming part thereof.

Fig. I is a side elevation showing the new design of an electric connector plug or similar article;

Fig. II is an end view from the left of Fig. I, showing the inlet end for the conductor wires;

Fig. III is an end view from the right or prong projecting end of the device of Fig. I; and

Fig. IV is a perspective view thereof.

I claim:

The ornamental design for an electric connector plug or similar article, substantially as shown.

WILLIAM H. COOK.
